UNITED STATES PATENT OFFICE.

EDWARD J. CRESSEY, OF WICHITA, KANSAS.

AUTOMATIC TELEPHONE RESPONDING APPARATUS.

1,138,734.

Specification of Letters Patent. Patented May 11, 1915.

Application filed October 14, 1913. Serial No. 795,099.

To all whom it may concern:

Be it known that I, EDWARD J. CRESSEY, a citizen of the United States of America, residing at Wichita, in the county of Sedgwick and State of Kansas, have invented a certain new and Improved Automatic Telephone Responding Apparatus; and I do hereby declare that the following is a full, clear, and exact description of the invention, reference being had to the accompanying drawings, forming a part of this specification.

The principal object of the invention is to produce telephone responses automatically, to predetermined acoustic records of a re-producing phonographic instrument, in which the responsive vibrations of the transmitter may be momentary or continuous. Second: to increase progressively the predetermined records, so as to effect the responsive words, numbers or accents in multiple coincidence. Third: to automatically control the movement of the record re-producing mechanism, at the end of a cylinder movement. Fourth: to automatically control, through an indicator, the movements of the record cylinder. Fifth: to govern the action of the record cylinder, for a limited or continuous record movement. Sixth: to record the calls transmitted phonographically to the re-producing instrument. Seventh: to effect a responsive bell call from the reproducing instrument automatically; and Eighth: to control the response of the bell call simultaneously with the movement of the receiver from the hook switch.

It is further the object to enable the subscriber to a telephone, upon a temporary absence from the home or place of business, to leave a predetermined phonographic record in communication with the telephone, which will respond arbitrarily and as predetermined, to any call made upon the telephone during the subscriber's absence, and for commercial purposes the invention is designed to afford a responsive key to an established code, whereby information is generalized, and also for the dissemination of business sales or daily telegraphic news items, the method whereby these results are obtained being shown in connection with the apparatus illustrated in the accompanying drawing, to which reference is now made, in which

like characters of reference indicate like parts, in all the figures of the drawings, and in which:

Figure 1. is a front view of the complete apparatus, the sound carrier being shown in communication with the mouthpiece of the telephone, and phonograph instruments showing the method in which the hook switch is operated, upon the transmission of the call electrically to the electro-magnets in the cabinet, on the box supporting the phonograph, portions of the front wall of the box being broken away, to show the motor and the storage battery, and electric connections between the motor and battery, showing also the telephone bell box. Fig. 2. is a plan view of the apparatus, as seen in Fig. 1, with the exception of the telephone bell-box portions of the box supporting the phonograph being broken away, to show the electric connections between the bell on the arm of the phonograph re-producer and the battery. Fig. 3. is a view looking inwardly from the right-hand end of the box supporting the phonograph, in which the end of the box, and the outer side of the cabinet are removed, on the line x, x , in Fig. 2, in which latter figure are seen the electro-magnets, which release the notched disk, and the call indicated, the circuit closed to the batteries to energize the motor, and the circuit closer to the bell, upon the movement of the cam away from the weighted pivoted lever, which falls to raise the hook switch of the telephone receiver. Fig. 4. is a view within the phonograph box looking in the direction of the left-hand end, and showing the box in transverse section, taken upon the line y, y , on Fig. 2, at which end of the box is seen the electric motor and the time-controlling wheel, and the reversing and spiral gear mechanism actuated by the motor. Fig. 5. is a transverse, sectional view of the phonograph box, taken on the line z, z , on Fig. 2, showing the phonograph record re-producing mechanism upon the top plate, a portion of the hollow arm, in which the bell is carried, being seen broken away, and the conducting wires leading to the battery, the eccentric cam being in a position to hold the record re-producing diaphragm holder in an elevated position. Fig. 6. is a view in detail of the indicator stop devices, the in-

2

dicator plate being broken away. Fig. 7. is a view of the cabinet, with the inner side plate removed, to show the time-regulating disk, the circuit closer to the bell, and the 5 weighted pivoted lever operating the hook switch of the telephone. Fig. 8. is a detail plan view of the time-controlling revoluble disk, and the movable socket plate for closing the notch in the disk, and producing a 10 continuous call. Fig. 9. is a modification of the eccentric shaft controlling the rise and fall of the record re-producing diaphragm holder. Fig. 10. is a plan view of the record re-producing instruments upon the 15 phonograph box, arranged to produce multiple responses. Fig. 11. is a broken view of the front side of the box, showing the measured stops. Fig. 12. is a side view of the arm supporting the record re-producing diaphragm in Fig. 11, in a position on the cam 20 shaft, when the response is made to the telephone call.

The permanent record of a predetermined code, either numerically or effected by vocal 25 utterance or specific language, is first made of record upon a record cylinder, 15, of a phonograph, by means of the recording pin 18 upon the diaphragm of the diaphragm holder 16, in the ordinary manner. These 30 features of the phonograph are made a part of my apparatus, which, as shown, comprises a box 20.

21 represents the top plate, 22, 23 the forward and rear side plates, respectively, 35 and 24 and 25 the right and left-hand ends, and 26 the bottom of the box. Upon the upper surface of the top plate 21 is a flat plate 27, slightly less in length and width to the dimensions of the top plate 21.

40 The record cylinder 15 is supported upon a cylindrical casting or body 28, which body or casting is located above the plate 27, at a point approximately equi-distant from the vertical line of the sides and ends of the box, 45 and mounted upon one end of a rotatable shaft 29, the outer end of said shaft being supported in shaft bearings in the upper end of standards 30, 30^x, upon the end portion of plate 27, in the direction of the end 25, of 50 the box.

Within the box, and upon the bottom 26, adjacent the end 24, are the storage batteries 31 and 32, and adjacent the other end 25 is located an electric motor 33, the conducting 55 wires being connected with the respective poles of the battery, and the motor in order to set in motion the motor, as further described.

Upon the motor shaft 36 is a band wheel 60 37, over which extends an endless band 38, which band extends upwardly through an opening 39, in the top plates 21 and 27 and over a band pulley 40, on the shaft 29, supporting the record cylinder 15. Upon this 65 shaft 29, adjacent the pulley 40, is a small

gear wheel 41, and between said gear wheel and the bearing for shaft 29 is a similar gear wheel 42. This latter gear wheel engages with a gear wheel 43, larger in circumference, which has a stud shaft 44, mounted in 70 a bearing on the upper end of a standard 45, secured at its lower end to the plate 27. The gear wheel 43 meshes with a gear wheel or idler 46, on the outer end of a rotary shaft 47, which end is mounted in a bearing upon 75 the upper end of a standard 48, in rear of the standard 45. The inner end of shaft 47 is mounted in the upper end of a standard 49. Upon the surface of the shaft 47 is a fine screw thread 47^x, extending nearly the entire length of the shaft. 80

A hollow arm 50 supports the record diaphragm 16^x, which as seen is outwardly curved, and its lower end portion connected with the inner end of a sleeve 51, slidably mounted on a longitudinal stationary shaft 52, immediately forward and parallel with the shaft 47, the said shaft 52 being supported in the upper ends of the standards 53 and 54. At the outer end of the sleeve is an inclined plate 55, having an outer curved end 56, provided with a threaded upper surface, which extends beneath and meshes with the spiral gear on shaft 47, (see Fig. 2).

57 indicates a coiled spring, which causes 95 a return movement to the arm 50, one end being secured thereto at 58, and the other end to the upper end of the standard 59; adjacent the gear reversing gear-wheel 48.

The upper portion of the hollow arm is 100 provided with a cup-shaped removable cap 60, an electrically operated bell 61 being secured to its inner surface. From the bell clapper magnets extend conducting wires, which are connected with other wires leading to the battery 32, as further indicated. For the momentary responses of the record cylinder, it is designed to hold the arm 50, carrying the diaphragm reproducer 16 normally out of contact with the record cylinder 15, to effect which result, a longitudinal round shaft 64, having a joint 64^x, further referred to, is mounted longitudinally upon the box, in advance of the record cylinder 110 15, having a journal at its outer end journaled in the upper end of a standard 65, upon which shaft is a large gear wheel 66, extending within a slot 66^x, in the top of the box, meshing with the small gear 41, on the record cylinder supporting shaft 29. Upon the shaft 64 is fitted an enlarged, longitudinal eccentric portion 67, the eccentric portion being nearly flat, so as to cause an instantaneous fall of the record cylinder. The

115 angular lifting arm 68, has an inner extension 68^x and is connected with the forward portion of the recording diaphragm holder 16, which arm bears upon the eccentric 67, and controls the responses as the shaft 64 is given a rotary motion, and in which the 120 130

further movement of the recording diaphragm holder is moved in the direction of the length of the record cylinder.

The place of starting of the diaphragm holder is controlled by an upright stop pin 70, which is movable in a longitudinal slot 71, in the top plate 21, of the phonograph box, and which is connected at its lower end with a movable bar 72, parallel with the inner surface of the front plate 22, of the box, the ends of the said bar being supported in the hangers 73, 73, as seen in Fig. 6. Upon the lower surface of the bar 72 is a longitudinal rack bar 74. Beneath and engaging with the said rack bar is a gear wheel 75, mounted on a rotary shaft 76, supported in a bearing 77, the outer end of the shaft extending through the front plate 22, of the box 20, and upon said end is a spring 20 indicator or hand 80, the outer end being provided with a pin 81. A circular indicator plate 82 is attached to the outer surface of the box, the shaft 76 extending through its center, and upon the peripheral 25 portion are indicator marks, spaced apart in the direction of the circumference of said plate, beginning at 1, for instance, and numerically to 99, or continued beyond, to any higher number desired. Immediately with- 30 in the lines of the numbers and in the outer surface of the plate 80, are perforations or indentations 83, which receive the pin 81 and hold the spring indicator 80 to the position opposite the number to which it is intended, for a response from the record cylinder, and which follows the movement of the eccentric shaft 67, the action of which is governed, as further explained.

Upon the upper surface and right-hand 40 end of the phonograph box 20 is an upright cabinet or box 85, as shown, narrow in width, and extending across the right-hand end portion of the box and plate 27, and provided with forward and rearward ends 45 86 and 87, respectively, and outer and inner side plates 88 and 89, respectively, the splined portion 64^x, of the round inner end of shaft 64 having the eccentric portion 67, being extended through the side plate 89, of 50 the cabinet or box 85.

The limit of duration of the action of the diaphragm record re-producer is controlled by a circular disk 90, upon the inner end of shaft 64, within the cabinet, in the periphery of which is a notch 91, this disk moving in a longitudinal slot 93, in the top plates 21 and 27, shown fully in Fig. 7. Above the disk, in the upper portion of the cabinet, are supported the two electro-magnets 94, the armature plate 95 being movable upwardly in contact with the poles 96, on the closing of the circuit. Beneath the armature is an insulator, with which armature is connected the pin 97, which pin moves vertically in a socket plate 98, on the inner sur-

face of the side plate 89, of the cabinet, the lower end of the pin engaging normally in the notch 91, in the disk 90, and being withdrawn therefrom on the upward movement of the armature plate 95.

An insulated lever 99 is pivoted at 100, to the inner surface of the side plate 89 of the cabinet, the short end of the lever being pivotally connected at 102, with the pin 97, a short distance below the armature plate 95, 70 the closing movement of which armature is slight. The long end of the lever 99 is insulated upon its lower surface. A circuit closer 103 extends beneath the long end of the insulated end of the lever, connected with the supports 104, upon the side 89, of the cabinet and insulated from each other. 75

From one of the binding posts 109^x, of the circuit closer are connected the electric circuit wires, one wire 109, leading to the 80 pole of the storage battery 31, and at 110 another conducting wire is connected with the other pole of the electric motor. Another conducting wire 112 is connected with the other binding post on the battery 31, 90 and leads to and is connected with the other pole of the electric motor 33.

The normal action of the pin 97 is to move over the peripheral portion of the disk 90, until the notch 91 comes opposite 95 the pin, when the pin enters the notch, and the circuit is open to the motor and battery. To make an extended, rotary movement of the disk, a socket plate 114 is fitted to slide on the spline 64^x upon the side of the disk 90 toward the side 89, of the cabinet, the outer circular flange 115, of which is movable over the outer periphery of the disk 90, so far as to cover the notch 91, in the disk 90. A semi-circular cam plate 116 is also 100 mounted eccentrically and slidably on spline 64^x and connected with the outer surface of the socket plate 114, its pointed upper end being directed upwardly. A triangular portion of the flange 115, of the 105 socket plate 114, is removed, to form a space or notch in said flange, at a point past the line of the notch 91, in the disk 90 the notch extending inwardly at 119, thence inclined outwardly, at 118, to the line of the inner 115 edge of the flange 115. A coiled spring 64^x, on the shaft 64, bears at one end against the cam 116, and at the other end against a pin 120, on the inner end of shaft 64. In the rotation of the shaft 64, the spring moves 120 the socket plate inwardly, so that the inner edge of the annular flange 115 is normally in contact with the pin 97, until a second call raises the pin, when the pin moves over the outer surface of the flange 115, until the 125 interval occurs that the pin again enters the space 118, and in moving along the inclined surface moves the socket disk outwardly against the tension of the spring, and remains in this position until the second call 130

135

1 occurs. To indicate the successive calls made, a thin spring plate 121 is connected at its inner end with the short end of the lever 99 and has its outer end extended to a position in contact with the periphery of a ratchet wheel 122, on the inner end of a short rotary shaft 123, extending through the end plate 86 of the cabinet, which also passes through the center of a flat indicator plate or disk 124, secured to said end, and upon which are indicator marks in the direction of the circumference of the disk, spaced apart, the spaces indicating the distance which the armature 95 moves in closing the circuit with the magnets 94. An indicator arm or hand 125, on the outer end of shaft 123, indicates the position on the indicator plate to which it is moved, coincident to the movements of the ratchet wheel 122.

20 Upon the upward movement of the armature, to release the pin 97, and the first rotative movement of the time-controlling disk 90, a pin 126, on the outer surface of the disk contacts with the yielding upper member of a circuit closer 126*, supported by the end plate 86, of the cabinet, from which extend the conducting wires 127 and 128. The wire 127 leads to one pole of the battery 32, and the other wire 128 leads to the electric bell, while a separate wire 129 leads from the other pole of battery 32 to the bell-clapper magnets of the cabinet.

30 The device for the automatic opening of the switch to the telephone consists of a lever 130, having a pivotal support 131, connected with the inner surface of the plate 89 to the cabinet. The inner end of the lever 130 is weighted at 132, properly to enable the other short end to raise a greater weight 40 at said end. Said short end of the lever 130 is provided with an arm 133, which extends through a vertical opening 134, in the outer side plate 88 of the cabinet, and upon said end is the horizontal flat plate 135, extending beneath the switch, and forming the hand-piece for raising the switch lever of the telephone, further referred to.

45 From the electro-magnets 94, in the cabinet 80, extend the conducting wires 137 and 138, which extend to and are connected in a suitable manner with the terminals of the electro-magnets 140, which energize the electric signal bell in the bell box 141 in the telephone circuit.

50 The speaking equipment shown is the ordinary desk telephone of a telephone system, the mouth-piece 142 being at the upper end of the standard 143, which latter is supported upon the base 144. 145 is the short lever switch supporting the receiver 146, the outer end of the switch lever resting upon the upper surface of plate 135. The conducting wires 147 lead from the receiver to the base of the standard, and the wires 148, 65 149, lead from the base to the bell box 141,

and are connected with electro-magnets in the usual well known manner. A sound-conducting flexible tube 150 is connected at one end with the mouth-piece 17, of the reproducing diaphragm holder 16, and upon 70 the other end is a socket 151, which is provided with cut segments 152, which bend over upon the inner surfaces of the mouth-piece 142, of the telephone, thus providing a conductor of sound from the diaphragm 75 of the telephone within the mouth-piece, and with the operating diaphragm on the diaphragm holder 16.

Upon the side of the cap 60, carrying the bell 61, is a circular opening 153, having an extended outer flange 154, extending around said opening. With this flange is connected one end of a branch sound-conducting tube 155, the other end being connected with the rear portion of the sound-conducting tube 150, the sound of the bell being conducted through tube 150.

80 In the telephone system, when a call is made upon any subscriber's telephone, the bell signal circuit of that telephone is closed 90 at the central office, and the bell magnets in the bell box energized electrically, to ring the bell, upon the box 141. The subscriber in the employment of the invention first prepares a code, of such a character as will 95 impart all the information desired to be given to any one calling the subscriber's telephone. This is made upon a record cylinder, in the ordinary manner, and may 100 consist of a series of numbers, which are known as code numbers, and are employed as a key to words or sentences in series, these numbers accompanying the word or phrase predetermined and printed upon a page of a telephone book, or upon the pages 105 of a specially prepared code book, accessible to the persons desirous of using the code, or for the purpose of calling the subscriber upon the telephone of the latter. Let, for instance, the numbers consecutively from 1 110 to 100 form a code, which precede the like number of sentences explanatory of the occupied hours and causes of absence from the place of business, or the time set for the return of a subscriber, as, for instance, let 115 the numeral 1 be followed by the explanatory words, setting a time from 9 a. m. to any hour and fraction of an hour in the 24 hours subsequent, when the subscriber will be at his place of business. The record cylinder 15 being made to respond to any one of these numbers, the movable hand 80, of the indicator 82, which has a scale of indicated spaces from one to ninety-nine, as seen in Fig. 1, in which the scale is divided 120 into ten equal parts, for convenient illustration. The position of the record transmitting diaphragm holder, in respect to the cylinder, is shown in the drawings at a point 125 about midway its length. Presuming that 130

this point is such that the pin of the phonograph record diaphragm is set directly upon the record surface, the movable arm 80 is moved circuitously, until the point of the pin 81 is opposite the point or scale number 45, the record under which number responds 45, indicating in the code book or page upon a basis of a quarter of an hour 8:15, which the record will, at the proper time respond 10 45. The movement of the indicator arm 82, to the point indicated on the scale simultaneously moves the rack bar 74 to the right, the stop 70 being in a position upon the left-hand side of the arm 68, connected with the 15 diaphragm holder arm 50, the position of the eccentric portion 67 being in the position to keep said arm and the diaphragm holder elevated. The time-controlling disk 90, as seen in Fig. 3, is of the same circumference as the rotary gear wheel 66, on the eccentric carrying shaft 64, this disk 90 being, as before explained, held by the pin 97, on the insulated plate on the armature 95.

25 Any person who desires to call the subscriber removes the receiver from the hook switch lever of his own or a public telephone in a telephone system, in the ordinary manner, calling at the same time the central 30 office by the number which indicates the subscriber's telephone in which the invention is installed. The plug being inserted at the central office, the electric circuit through the bell box 141, in the office of the subscriber, 35 as seen in Fig. 1, energizes the magnets 140, the current being conducted by the conducting wires 137, 138, to the magnets 94, in the cabinet 85, in the box 20, of the responding apparatus, which now draws up 40 the armature 95, releasing the pin 97 from the notch 91, in the time-controlling disk 90. This action of the armature closes the circuit closer 103, and the current from the battery 31 is conducted over the wires 110, 112, 45 to the electric motor 33, and the power is transmitted through the belt 38, to the record cylinder shaft 29, thence to the controlling gear wheel 66, through the small gear 41, and the shaft begins to revolve and 50 starts the movement of the time-controlling disk 90, at which movement the weighted end 134, of the lever 130 falls from the cam plate 116, raising the outer end, and thereby raising the hook switch lever 135, on the telephone stand 143 of the subscriber, and the telephonic communication is at once established between the record cylinder and the diaphragm of the receiver, at the ear of the person calling the subscriber. Upon the 60 instant the lever 130 opens the switch lever 135, the pin 126 on the time-controlling disk 90, closes the circuit through the circuit closer 126^x, and the battery 32 energizes the bell clapper on the arm 50, of the diaphragm holder, and the sound of the bell reaches the

ear of the person through the branch tube 155 and tube 150, connected with the mouth-piece of the telephone, and the circuit is open again. In passing the circuit closer, the rotative movement of the eccentric 67 70 permits the arm 68 to fall, so as to bring the sound-transmitting point of the diaphragm 16^x, upon the record cylinder, and the record responds 45, which is transmitted through the diaphragm of the mouth-piece 75 151, in the subscriber's telephone to the ear of the person holding the receiver and making a call. The person consulting the code, under the numerals 45, finds the answer, "45 will return at 8:15 p. m." The upward 80 movement of the armature, which has moved the ratchet disk 122 a partial distance, has, in the meantime, moved the pointer 125 one space, thus indicating that one call has been made during the absence of the subscriber to 85 the telephone. The call now having been made and the response given, the disk 90 continues to rotate, until the full revolution is made, and the notch 91 comes into position beneath the pin 97, on the armature, 90 and the armature falls therein, and the circuit is broken, the action of such parts being consummated, and following which act the eccentric again moves the diaphragm holder upwardly and the record ceases. 95 Should the call require a movement of the diaphragm holder 16 back to number 1, the indicator arm 80 is drawn out a slight distance, releasing the pin, and moved back to the point or space marked 1, on the indicator plate 82, and the arm 68, on the holder, now moves automatically, the spring 27 contracting and carrying the holder back to the position seen in dotted lines in Fig. 2.

The numbers on the record may be serially, from the smallest to the highest number practicable, as the space of the record cylinder will contain within a short distance a great number, the stop being set as before at the starting point, and from this point so long as the circuit is open, the diaphragm holder moves under the control of the threaded shaft 47, in a degree of slight speed sufficient to impart a response of words instead of numbers, and such information as is recorded upon the record. 105

In the event that there should be another call, or one or more calls made upon the subscriber's telephone, during the first call, or immediately afterward, the pin 97, on the armature, instead of moving over the periphery of the disk 90, is raised momentarily, and the spring 120, on the shaft 64 is permitted to expand, forcing the cam 116 and the socket plate toward the disk 90, the 115 cam moving past the end of the lever 130, so that the switch lever 133, on the telephone standard, remains in an elevated position and the circuit is closed, and the flange 115, on the socket 114 moves over and closes the 120

socket 91, in the disk 90, the pin 97, meanwhile, moving over the surface of flange 115, past the notch and during another revolution, until the pin enters the opening 117, 5 and striking the incline 118, moves the socket plate outwardly, and at the completion of the last call enters the notch 91, as before, and the signal circuit is opened. If necessary there may be employed one or 10 more signal lines in the operation of the armature mechanism, it being observed that in the continued rotation of the disk 90, the movement of the diaphragm holder of the phonograph is repeated.

15 The multiple succession of numbers, in which the numbers are repeated, and in which the higher numbers may be conveniently obtained and an unlimited permutation obtained, is seen in the apparatus illustrated in Fig. 10, which, being with the modifications further described, the same as in Fig. 1.

As seen in Fig. 10, a longer record cylinder 160, upon the record of the code numbers or characters, or even responses in words, is placed upon the extended casting or cylinder 161, on the revoluble shaft 162, and thus providing for the increase in numbers of the record diaphragm holder arm 50, 30 and diaphragm holders, which, as seen in Fig. 10, are the same as in Fig. 1, there being a recoiling spring 163, connected with each arm 50, and with the standards 164, the eccentric portions 165, 166, on shaft 64, being in multiple.

From the mouth-piece of one sound transmitting diaphragm extends a sound-conducting tube 167, and from the other a tube 168, which latter is connected at 169 with the tube 168, the tube 168 being connected with the mouth-piece of the telephone, in the same manner in which the tube 150 is connected in Fig. 1. The arms 169 and 170, from the diaphragm holders 50, extend outwardly, 45 and upon said arms yielding spring plates 171, 172 are laid between upright portions of outwardly-extended flanges 173, on the plate 174, and the plate 175, the flanges 176 on the latter plate being as seen closer together. The spaces between these flanges are seen indicated from 1 to 9, on plate 174, and in plate 175 from 1 to 9, including a cipher, the response on the record cylinder being in like ratio, and the wide and narrow 55 spaces between the flanges differentiate the length of time between the stops for long and short responses, or giving long and short sounds, one following another. In Fig. 10, which omits the bell, the sound of a bell is made on the record cylinder.

60 The record cylinder may be further prepared for giving responsive information of considerable length, such as, for instance, the telegraphic news items which are received after papers have gone to press. In

this instance, the apparatus in the telephone book is given an appropriate telephone number, which may be called a "respondo" telephone number in the book. The call being made for the respondo number of the apparatus in the usual manner, through the telephone of the newspaper office in which the apparatus is installed, an inter-communicating telephone switch connection with the central office of the telephone system is 70 placed in electric connection with the apparatus, and the circuit closed gives the responses on the record cylinder to any one calling the respondo telephone number. The length of the news item is afforded by permitting the diaphragm holder to move correspondingly to a certain point, and stop or continue to a point in which the responsive speaking ceases, and then returns to the beginning and resumes the responsive information and v. This is attained by the joint 64°, on the shaft 64, before referred to, adjacent to the part which enters the cabinet and supports the time-controlling disk, and providing a detachable joint 64° by means of which portion of shaft 64, and one end of the self-acting eccentric shaft 178 are coupled. This shaft is provided with a longitudinal slot 179, in the flat portion 180, of the cam surface, in which is pivoted at 181, one end of a longitudinal strip 182, the other end being caused to move outwardly by means of a curved spring plate 183, in the lower surface of slot 179. Instead of the gear wheel 66, a gear wheel 184 is provided with a series of notches 185, upon the inner surface of the hub 186, these notches being slightly apart in the circumference of said portion of the hub, and adapted to permit the end of strip 180 to move in and out 100 of the notches with little friction. The sliding stop 187 is a sleeve, having an opening 188 at the upper surface, and said surface inclined at 189. A set screw 190 controls the stop at any joint in the line of shaft 179. 110

Nearly three-fourths of the outer surface of shaft 178 moves over the notches 185, hence the strip 182, which forms the eccentric portion of the shaft 178, is forced outwardly in one of the notches 185. When the first 115 movement of the disk 90 occurs, it makes about one-half a revolution to bring the shaft 178 into the position as seen in Fig. 9, when the weight of the arms 68, on the recording diaphragm, which is moved by the spiral shaft 47, comes into contact with the eccentric strip 182, forcing the strip inwardly, disengaging the strip from the notches 185, and the arm moves along the flat surface 180, until it reaches the inclined 120 surface 189, of the sleeve 187, this movement of the diaphragm holder being caused by the action of the spiral shaft 47. Upon reaching the upper portion of the inclined surface 187, the arm of the diaphragm holder re- 125 130

leases the strip 187, which moves upwardly in the notch 188 and engages again with one of the notches 185, in the hub 186, and the shaft begins to revolve and raises the 5 arm 68, of the diaphragm holder, disengaging the plate 55 from the spiral shaft 47, and the spring 57 returns the diaphragm holder to the original starting point.

One of the distinguishing features of my 10 invention is that the repetition of the responses of the phonograph is continued automatically, following one closure of the telephone circuit, in which interval of time the repetition of the sounds, words and sentences may be obtained, thus prolonging the 15 time, and making the service commercially possible. In like manner, a multiple series of sounds, in orderly succession, embracing a multiple series of members, may be transmitted, without interruption. Furthermore, the motor circuit, in my invention, is controlled directly by the signal circuit of the telephone, hence obviating the necessity of relays and other electrical combinations.

25 It is obvious that the electrical connections and the apparatus may be varied, to conform to any changes in the assemblage of parts of the phonographic apparatus, and the parts modified in any preferred manner. 30 Having fully described my invention, what I now claim as new and desire to secure by Letters Patent is:

1. In a combined phonograph instrument and telephone, a signal circuit, and an electro-magnet and armature in the signal circuit, a motor actuating the phonograph, and motor circuit-closing mechanism acting to prolong the closing of the armature in the one closing of the signal circuit.

40 2. In combined phonograph and telephone instruments, a signal circuit from the telephone circuit, and an electrically energized motor actuating the phonograph in an electric circuit, a circuit closer controlling the motor circuit, an electro-magnet, and an armature controlled by the signal circuit of the telephone controlling the closing of the motor circuit, and mechanism controlled by the phonograph acting to prolong the 50 closing of the motor circuit in a single closing of the signal circuit.

55 3. In combined phonograph and telephone instruments, a signal circuit from the telephone circuit, an electro-magnet and armature controlled by the signal circuit, a motor in a motor circuit, and a circuit closer, an electro-magnet, and a bell in an electro-magnet circuit, and a circuit closer, a revolute time controller actuated by the phonograph 60 and controlled in its movements by the closing of the signal circuit and acting to close the circuit closer to the electro-magnet bell circuit of the phonograph.

65 4. In combined phonograph and telephone instruments, a signal circuit in the telephone

circuit, an electro-magnet circuit for the phonograph in electric connection with the signal circuit, a motor in a motor circuit, and a circuit closer, a revolute time-controlled disk actuated by the motor, and an 70 armature controlling the closing of the circuit closer of the motor-circuit, which is operated by the signal circuit and releasably connected with the revolute disk.

5. A combined telephone and phonographic sound-producing apparatus, consisting of a phonograph, and a telephone electrically operated means on the phonograph for imparting movement thereto, and electrically-controlled apparatus in the signal 75 circuit of the telephone acting to hold the circuit closed and which is continuously operated in the closing of the signal circuit until a complete repetition of the record response has been made to the last telephone 80 circuit closing call.

6. In combined phonograph and telephone instruments, a phonograph and a telephone and a telephone signal circuit an electrically energized motor actuating the phonograph, 90 a motor circuit and a circuit-closing switch, an electro-magnet circuit in the signal circuit of the telephone, and an armature, and a revolute notched disk an armature extension acting to close the motor circuit, and an 95 engaging device on the armature adapted to engage the notched disk and control its rotation.

7. In combined phonograph and telephone instruments, an electrically energized motor 100 actuating the phonograph, and a circuit closing switch, an electro-magnet circuit in the signal circuit of the telephone, an armature for the electro-magnet, and a pin controlled by the armature, and a combined time-controlling notched disk and a socket plate self-acting to close the notch in said disk and normally held from movement by the pin on said armature.

8. In a time regulating device for phonographs, an electro-magnet, and an armature, a pin upon the armature, a rotary shaft, and a notched disk thereon upon the periphery of which the said pin is adapted to bear, and a self-moving sliding socket plate rotatable 115 in unison with said disk having a flange adapted to move over the surface of the disk and having its inner edge normally in contact with the said pin and provided with an inclined pin-guiding, notch past the line 120 of the notch in said disk.

9. In a time-regulating device for phonographs, a motor-operated rotary shaft, an electro-magnet, an armature, a notched disk on said shaft, and a socket plate rotatable in 125 unison with said disk having an inclined notch past the rotary portion closing said notch, a spring on the said shaft acting to move said socket in the direction of said disk, and a pin controlled by the armature 130

- normally retaining the socket plate from moving over the notch in said disk and adapted to move over the surface of the flange of the socket plate in a repeated movement of the armature.
- 5 10. In a time-regulating device for phonographs, a rotary shaft, a notched disk thereon, a sliding socket plate keyed to slide on said shaft and having a portion movable over the notch in said disk, and a notch in said portion past the line of the notch in said disk, a spring on said shaft actuating the closing of the socket plate, and a pin which is normally movable over the periphery of said disk and normally in contact with the inner edge of the flange of the socket plate.
- 10 15. In combined telephone and phonograph sound-transmitting instruments, consisting of a phonograph and a telephone, an electrically-operated motor-actuating the phonograph, a rotary shaft actuated by the motor and time-controlling mechanism on said shaft controlled by the signal circuit of the telephone, and a cam on said shaft, and a weighted lever controlled by said cam adapted to raise the switch lever of the telephone circuit.
- 20 25. In time-regulating devices for phonographs, a motor-operated shaft, a notched disk on said shaft, and a spring-actuated sliding socket plate keyed on said shaft and having a portion movable over the notch in said disk and an adjacent portion provided with an inclined notch, an electro-magnet in the signal circuit of the telephone, an armature controlled by the magnet, a pin on the armature movable over the surface of said disks, a cam on said rotary shaft connected with said socket plate, and a weighted pivoted lever for controlling the telephone switch which is adapted to be operated by said cam in the normal movement of the pin upon said disk.
- 30 35. In combined telephone and phonograph sound-transmitting instruments, a signal circuit from the telephone, and an electro-magnet, and an armature controlled by the signal circuit, an electric motor actuating the phonograph record-carrying and sound-re-producing mechanism in an electric circuit, and a circuit closer controlled by the armature, a rotary shaft actuated by said mechanism, and an eccentric on said shaft controlling the movements of the sound-re-producing mechanism.
- 40 45. In the mechanism for controlling phonographs, a motor and a motor circuit, and an electro-magnet, and an armature acting to close the motor circuit, a rotary shaft on the phonograph, and a power-transmitting wheel actuated by the phonograph mechanism, an eccentric controlling the movements of the record re-producer, and a time-controlling disk controlled by the
- 50 55. armature and actuated by said power-transmitting wheel.
- 60 65. In a phonograph, the combination with the record cylinder and sound-re-producing diaphragm and holder, an indicator plate having numerical registrations thereon corresponding numerically with the registrations on the record cylinder, a stud shaft, a pointer arm thereon adapted to be held from movement at any point upon the indicator plate, and stop mechanism controlled by the pointer arm controlling the movements of the diaphragm holder.
- 70 75. In a combined telephone and phonograph instrument, the combination with means on the phonograph for automatically closing the telephone circuit, of a record indicator of the record on the recording cylinder of the phonograph, a stud shaft and a rack, and a gear wheel on the stud shaft engaging with said rack a movable indicator arm, on the stud shaft, and means on said rack bar controlled by the indicator arm to control the diaphragm holder in its movement from any pre-determined point.
- 80 85. In a combined telephone and phonograph instrument, the combination with the record reproducing devices and with means on the phonograph for automatically closing the telephone circuit and with the motor on the phonograph, of a rotary shaft actuated thereby, and eccentrically operable devices on said shaft acting to cause repeated reciprocal movements of the record-re-producing devices.
- 90 95. In a phonograph instrument, the combination with the record cylinder, and with motor actuating the mechanism controlling the record cylinder and sound-re-producing devices, of a rotary shaft actuated thereby, and eccentrically-operable devices on said shaft acting automatically to cause a repeated movement of the sound-re-producing devices of the phonograph.
- 100 105. In a combined telephone and phonograph instrument, the combination with the record reproducing diaphragm, and with means on the phonograph for automatically closing the telephone circuit and with means for conducting the sound produced by the record-re-producing diaphragm to the receiving diaphragm of the telephone, of means for setting the diaphragm at any pre-determined point above the record cylinder at which the response is to be conducted to the telephone, and means acting automatically to hold the diaphragm normally from its record-re-producing sound movement and cause its return to the starting point.
- 110 115. In a combined telephone and phonograph instrument, and in combination with means on the phonograph for automatically closing the telephone circuit, and with the motor actuating phonograph, of a rotary shaft actuated by the motor having an ec-
- 120 125. 130.

- centric portion adapted to control the repetition of the sound-re-producing movements, a reciprocating rack supported on the phonograph, a gear wheel actuating the rack 5 in its movements, a stud shaft supporting the gear wheel, and a pointer arm on the stud shaft, engaging devices on the pointer arm, and an arm on the rack acting to control the movement of the sound re-producer.
- 10 21. In a combined telephone and phonograph instrument, in combination, automatic means on the phonograph for closing the telephone circuit, automatic means co-acting to produce pre-determined responses 15 phonographically, and automatic means set in motion by the closing of the circuit for causing a repetition of the responses following the one closing of the telephone circuit.
22. In a combined telephone and phonograph instrument, a pivoted lever having one end engaging with the switch lever of the telephone, and means co-acting with the other end adapted to raise said end of said
- lever and close the telephone circuit, a rotary shaft on the phonograph actuated by its 25 motor, and a cam on said shaft adapted to raise the inner end of the lever and open the telephone circuit.
23. In a combined telephone and phonograph instrument, a pivoted lever having 30 one end extending beneath the switch lever of the telephone, and a weight upon the other end, a rotary shaft actuated by the motor on the phonograph; a conductor of sound leading from the phonograph to the telephone, and a segment cam on said motor-actuated shaft adapted to rotate in the path of the weighted end of said cam and raise said arm in a partial rotative movement and release said arm in the completion of said 35 40 movement.
